BROOM SEWING APPARATUS

Robert E. Groom, near Greensboro, N. C.

Application October 22, 1938, Serial No. 236,535

4 Claims. (Cl. 112—6)

This invention relates to a selfstarter mechanism for a broom sewing machine and more especially to a mechanism capable of rotating the vise which grips the broom from normal position to sewing position.

In the conventional broom sewing machine a vise is employed for gripping a bunch of broom corn or other broom material while this material is being stitched together by a suitable cord. Before cord is placed in the broom by the stitching mechanism, it is necessary to lift or to rotate the vise containing the broom, from normal position to stitching position, after which the vise and the broom will be returned by conventional driving mechanism to normal position as the broom is being sewed, a portion of the conventional driving mechanism for moving the broom holder to normal position. Heretofore, it has been a practice for the operator to manually lift the vise from normal position to sewing position. Since the normal production of brooms is very high in mechanism for this type the operator will have to lift this vise many times during the day.

It is therefore an object of this invention to provide a power driven starting means for a broom sewing machine of the class described, comprising a driven pulley on the broom sewing machine which is adapted to be contacted at the desired time by an eccentric which, in turn, will be rotated to cause the vise containing the broom to move from normal position to sewing position.

It is another object of this invention to provide a broom starting mechanism of this type which is easy to install, simple in construction, economical to manufacture and easy to operate.

Some of the objects of the invention having been stated other objects will appear as the description proceeds when taken in connection with the accompanying drawings, in which:

Figure 1 is an isometric view showing my invention in bold lines and showing the conventional parts in dotted lines;

Figure 2 is an elevation of a portion of a broom sewing machine showing a portion of my invention applied thereto;

Figure 3 is a view similar to Figure 2 but showing the parts in a slightly different position;

Figure 4 is an elevation, looking at the left hand side of Figure 2 showing the vise which holds the broom both in bold line and dotted line positions;

Figure 5 is an elevation looking at the right hand side of Figure 2.

Referring more specifically to the drawings, the numeral 10 denotes the framework of a broom sewing machine in which is rotatably mounted a shaft 11, this shaft having a pulley 14 thereon and also a cam drum 12. The pulley 14 is driven by a suitable belt 15 from a source of power, not shown. Also pivoted as at 16 is a vise 17, the upper end of which is adapted to grip the opposed sides of a broom 13. This vise may be rotated from bold line position (Figure 10 4) to the dotted line position when it is desired to sew a row of stitches 20 into the broom.

Vise 17 occupies the position shown in bold lines when in normal position in Figure 4, but when it is desired to sew the row of stitches 20, it is swung to dotted line position, after which the vise will return to bold line position by virtue of a conventional driving mechanism. It is during this return that the row of stitches 20 are placed in the broom 13. Since the vise 17 is very heavy it is evident that much energy is required to push the same from bold line position to dotted line position. This is especially true in view of the fact that thousands of rows of stitches are sewed during a day, and each time a row 20 is sewed it is necessary to move the vise from bold line position to dotted line position.

I have therefore provided a power driven mechanism for moving the vise and the broom from normal position to sewing position. This device is shown in bold lines in Figure 1 and comprises an eccentric wheel 25 which is rotatably mounted as at 26 on frame 27, said frame having its lower end pivoted as at 28a to the broom machine framework 10. The wheel 25 has a friction covering 28 secured to a position of the periphery thereof. This covering is preferably made of rubber and partially surrounds the wheel 25, thereby leaving a low space 29 in which there is no covering. Secured around the shaft 26 and adjacent the pulley 25 (Figure 4) is a grooved pulley 30. This pulley has secured thereto, one end of a cable 31 as at 32, this cable extending upwardly over a sheave pulley 33 which, in turn, is supported by an eye bolt 34. The bolt 34 has its upper end adjustably mounted in one end of bracket 35, said bracket being secured to the upper side of framework 10 by any suitable means such as stud bolts 36. The eye bolt 34 is confined in the end of bracket 35 by any suitable means such as nuts 37. The other end of cable 31 is secured to a hook 38, and the hook is secured in Z-shaped plate member 39. The plate member is slidably mounted around a shaft 40 which, in turn, is secured in the upper portion of the vise 55

17. Also disposed around shaft 40 is a compression spring 41.

When the vise 17 is in normal or bold line position as shown in Figure 4 the frame 27 and its associated pulley 15 is in the position shown in Figure 2. At this time it is seen cover 28 of the pulley does not engage the belt 15 which is rotating on pulley 14. The frame 27, however, is held in this position by means of suitable tension springs 42. When it is desired to rotate the vise to sewing position it is necessary to rotate the frame 27 until the cover 28 on the periphery of pulley 25 engages the belt 15. When this is done the pulleys 25 and 38 will be rotated by this belt 15 until the low space 29 is reached. During this rotation of the wheel 25 the cable is wound around the pulley 30 in the manner shown in Figure 3 to cause the vise 17 to be drawn to dotted line position in Figure 4. The broom is now ready for a sewing operation by suitable oscillating needles, not shown, which move through the looping eyes 65 and 66, and thus a line of stitches will be formed in the broom while it is moving to bold line position in Figures 4 and 5.

25. In order to provide an easy means for bringing the lining 28 into contact with the belt 15 I have constructed a mechanism whereby a hand or foot of the operator can be brought into play for accomplishing this result. This mechanism comprises an eye bolt 44 which is secured in the upper end of frame 27, said eye bolt having secured to one end thereof a cable 45 which passes over pulley 46 and has its other end connected to an eye bolt 47, said eye bolt 47 being secured to the upper portion of a lever 48 as at 49. The lever 48 is pivoted intermediate its ends as at 50 to a bracket 51. It will be noted that the upper end of this lever has a handle 52 which may be engaged by the operator's hand and also has a pedal 55 which may be engaged by the operator's foot. Bracket 51 is secured to the framework 18 by means of bolts 56. This bracket has a set screw 57 therein, the end of which is adapted to contact the lever 48 at a point above pivot 50 when the parts are in normal position. In other words, the end of set screw 57 acts as a stop to prevent the lever 48 from swinging too far in a counterclockwise manner in Figure 5. A suitable lock nut 58 is also secured around set screw 57 to lock the set screw in an adjusted position. A similar set screw 59 is provided below the pivot point 50 and the end of this set screw is adapted to be contacted by the lower portion of the lever 48 when the operator places his foot on the treadle 55 or when the handle 52 is operated manually to rotate the lever 48 in a clockwise manner. Likewise this set screw has a lock nut 60 therearound.

60. When it is desired to place the machine in operation, that is, to move the vise 17 and the broom 18 to sewing position as shown in dotted lines in Figure 4, the operator places his foot upon the pedal 55 (Figure 5), which rotates the lever 48 in a clockwise manner. This rotation 65 will place tension upon the cable 45 and thereby draw the wheel 25 into contact with the rotating belt 15 in Figure 2. Since the high side or the cover 28 of wheel 25 will contact the belt 15 it is evident that rotation will be imparted to the 70 wheel 25 to cause the cable 31 to be wound around the pulley 30 in the manner shown in Figure 3, at which time the vise 17 will be drawn to sewing position as shown in dotted lines in Figure 4. After the wheel 25 has been rotated far 75 enough to cause the high side of the wheel to

move off of the belt 15 the low periphery 29 will not contact the belt; consequently the movement of the vise will automatically stop at this time. Then upon the release of pressure upon the treadle 55 by the operator the wheel 25 will return to normal position as shown in Figure 2 by virtue of conventional driving mechanism and the expansion of spring 41. Likewise, the frame 27 will also return to the normal position as shown in Figure 2 by virtue of tension spring 42.

10. It is very important that the set screw 59 be positioned so that when the lower portion of lever 48 strikes the end of the same that the wheel 25 will be moved enough to cause only the lining 28 to contact the belt 15. It is not drawn close enough for the low periphery 29 to contact the belt 15; consequently it is only while the lining 28 contacts the belt 15 that the vise 17 is drawn to sewing position. Figure 3 shows the position of wheel 25 after it has completed its rotation, 20 but prior to its return to normal position.

15. The function of the spring 41 (Figures 1 and 4) is to act as a shock absorber. When the wheel 25 is first drawn into contact with belt 15, very often a sudden jerk will be imparted to this wheel 25 to cause the cable to rotate the vise 17. By providing this spring, the sudden jerk is absorbed and the vise 17 is gradually drawn to sewing position.

20. It is seen from the drawings that adjustment 30 of the initial position of the vise 17 can be made by merely tightening or loosening the lock nuts 37 which support the sheave pulley 33. Likewise the initial position of the frame 27 which carries the pulley 25 can be adjusted by manipulating 35 the lock nuts on eye bolts 44 and 47.

25. In the drawings and specification there has been set forth a preferred embodiment of the invention, and although specific terms are employed, they are used in a generic and descriptive 40 sense, only, and not for purposes of limitation, the scope of the invention being set forth in the appended claims.

I claim:

1. In a broom sewing machine having a vise 45 for holding the broom during a sewing operation, said vise being pivoted intermediate its ends and having broom holding means in its upper end, a power driven shaft having a pulley with a belt thereon, a pivoted frame having a wheel rotatably mounted therein, friction means covering less than the whole periphery of the wheel, means for moving the wheel into contact with the belt on said pulley, a grooved pulley secured on one side of the wheel and having a cable secured 55 thereto, the other end of the cable being secured to the vise, whereby contact between the belt and the wheel will cause rotation of the wheel to wind the cable on the grooved pulley to move the vise from normal to sewing position.

2. In a broom sewing machine having a vise for holding a broom and being mounted for movement past the sewing point in the machine, a driven pulley in the machine, a driving belt on the pulley, a frame having a wheel mounted therein, friction means covering less than the whole periphery of the wheel, manually or pedal- 65 ly operated means for moving the wheel into contact with the belt, and a cable connection between the wheel and the vise for moving the vise past the sewing point of the machine while the friction portion of the wheel is in contact with the belt.

70. 3. In a broom sewing machine having a vise 75

5 pivoted intermediate its ends and constructed to occupy a normal position remote from the sewing point of the machine, a pulley in said machine having a driving belt thereon, said vice having means for holding broom material to be sewed as the material passes the sewing point of the machine, means for moving the vise with its broom material past the sewing point of the machine prior to a sewing operation, said means comprising a pivoted frame, a wheel in said frame, friction means covering less than the whole circumference of the wheel, a winding pulley and cable associated with said wheel and connected to said vise, means for moving the wheel into contact 10 with the belt while the belt turns the wheel through a portion of a revolution to wind the cable on the pulley to move the vise past the sewing point of the machine.

4. In a broom sewing machine having a frame, a pulley mounted for rotation in the frame and having a driving belt thereon, a pivoted frame associated with the pulley and belt and having a wheel and winding drum mounted for rotation thereon, said wheel having a friction surface over a portion of its periphery and having a low place disposed between the borders of said friction surface, a broom holding vise swingable past the sewing point of the machine, a cable connected 10 to said drum and to said vise, means for moving the pivoted frame to cause the friction surface to contact the belt to impart rotation to the wheel and drum and to thereby move the vise and its broom past the sewing point of the machine 15 while the needles are idle.

ROBERT E. GROOME.
